PRESSING MACHINE WITH WORK SUPPORT

Filed Jan. 19, 1929

UNITED STATES PATENT OFFICE

PHILIP N. BRAUN, OF SYRACUSE, NEW YORK, ASSIGNOR TO THE PROSPERITY COMPANY INC., OF SYRACUSE, NEW YORK, A CORPORATION OF NEW YORK

PRESSING MACHINE WITH WORK SUPPORT

Application filed January 19, 1929. Serial No. 333,614.

This invention relates to garment and laundry pressing machines and has for its object a particularly simple and efficient work support for holding the portion of the work which overhangs or is unsupported by the pressing element so that the weight of the normally unsupported or overhanging part of the work will not disarrange the part of the work on the pressing element.

10 The invention consists in the novel features and in the combinations and constructions hereinafter set forth and claimed.

In describing this invention, reference is had to the accompanying drawing in which 5 like characters designate corresponding parts in all the views.

Figure 1 is a fragmentary side elevation of a pressing machine embodying this invention.

20 Figure 2 is a front elevation of parts seen in Figure 1.

Figure 3 is a plan view illustrating the operation of the work support when pressing a shirt, the work support being indicated 25 by dotted lines.

Figure 4 is a view similar to Figure 3 with a work support out of its operative position.

Figure 5 is an enlarged sectional view taken approximately on the plane of line 30 5-5, Figure 2.

Figure 6 is a fragmentary perspective view of the upper portion of the work support, the handle being omitted.

This invention comprises, generally, a 35 work support for the portion of the work unsupported by the lower pressing element or platen of a garment and laundry pressing machine, said support being located in front of the lower pressing element or buck 40 and shiftable relatively thereto into and out of operative relation to the pressing element.

In pressing certain articles as shirts, the 45 collars and cuffs are pressed in one operation so that the major portion of the garment is hanging over the edge of the pressing element. The weight of this overhanging portion tends to disarrange the cuffs and collars.

I have here illustrated my invention as 50 embodied in the conventional type of press-

ing machine including a lower pressing element or buck 1 and head 2 movable toward and from the buck 1. The buck 1 is mounted on a gooseneck or bracket 3 which in turn is mounted on a table 4 carried by a frame 5. 55 The head 2 is carried and operated in any suitable manner. The operation of the head forms no part of this invention.

6 designates the work support for the portion of the garment or work unsupported by 60 or on the pressing face of the buck 1, this support having a head 7 normally arranged substantially the level of the buck 1 and the support being shiftable to carry its head 7 out of operative position so as not to be an 65 obstruction when it is not used in the pressing of the garment.

As here illustrated the support 6 is mounted to shift vertically to carry the head 7 from a position close to the table 4 into its normal 70 position at nearly the level of the buck.

In the illustrated embodiment of my invention, the support is a shelf extending angularly from one or more upright members which slide vertically through the table, and 75 the shelf is preferably carried by two upright arms or rods slidable through guides 8, mounted on the table. The guides 8 are provided with means such as spring pressed poppets 9 which engage with depressions in the 80 upright rods to hold the support 6 in its elevated position, preferably the head 7 is in the form of a bail bent at an angle to the rods. A suitable cross bar 9^a connects the 85 opposing arms of the bail for service as a handle to lower and elevate the support.

In operation, when the cuffs and collars are to be ironed the support is elevated into the position shown in Figures 1 and 2, by pulling upwardly on the handle 9^a and the shirt applied to the buck, as shown in Figure 3, in which the support 6 underlies the yoke of the shirt and supports the shirt so that the weight thereof does not pull the cuffs and collars off the buck 1 before the head 2 comes down on the buck 1. When another portion of the shirt or another garment is being pressed, as 95 shown in Figure 4, where the weight of the overhang is not sufficient to disarrange the shirt, the support is moved downwardly into 100

the dotted line position shown in Figure 1.

By my invention, the same pressing machine can be used to press different classes of work and at the same time is adaptable when necessary to press the cuffs and collars of shirts, this operation, particularly the cuff pressing operation, having heretofore been performed on a special pressing machine.

What I claim is:

1. In a pressing machine, an elevated plat-
10 en pressing element and a work support located in front of the pressing element to support that portion of the work which is unsupported by the pressing element, said work support including a plurality of supporting rods having horizontally disposed upper portions to form a head; guide means in which said supporting rods are slidably mounted for shifting the work support into and out of juxtaposition to the pressing element.
2. In a pressing machine, a table, an elevated pressing element supported on the table, and a work support for the portion of the work unsupported by the pressing element, the work support being located in front of the pressing element, said work support including supporting rods mounted for vertical sliding movement and bent over at their upper ends toward the pressing element to form a head substantially at the level of the pressing element when said work support is in raised position, guide means in which said rods are mounted for vertical sliding movement to shift the work support into and out of operative relation to the pressing element.
3. In a pressing machine, a frame, including a table, a pressing element, brackets supporting the pressing element elevated above the table, a work support for that portion of the work which is unsupported by the pressing element, the work support comprising a rod bent in a form having two substantially upright portions and a center bail portion substantially horizontally disposed, guide means in which said upright portions are slidably mounted to shift said work support vertically relative to the table to carry the bail portion into and out of position substantially level with the pressing element, and means for holding the support in its elevated position.
4. In a pressing machine, a frame includ-
55 ing a table, a pressing element, brackets supporting the pressing element elevated above the table, a work support for that portion of the work which is unsupported by the pressing element, the work support comprising an upright member slidably mounted in the table in front of the pressing element and having an angular horizontal shelf portion, guide means in which said upright member is slidably mounted to shift said work support vertically relative to the table to carry the shelf into and out of position substantial-
65 ly level with the pressing element and spring

pressed latch means engaging with a depression in said upright slidable member to hold the work support in its set position.

5. In a pressing machine, a frame includ-
70 ing a table, a pressing element, brackets supporting the pressing element elevated above the table, a work support for that portion of the work which is unsupported by the pressing element, the work support comprising substantially parallel upright members slidably mounted in the table in front of the pressing element and having an angular horizontal shelf portion, guide means in which said upright members are slidably mounted to shift said work support vertically relative to the table to carry the shelf into and out of position substantially level with the pressing element, spring pressed latch means engaging with depressions in said upright slidable members to hold the work support in its set position, and a cross member between the upright members to serve as a handle for shifting the position of said work support.

In testimony whereof, I have hereunto signed my name at Syracuse, in the county of Onondaga, and State of New York, this 17th day of January, 1929.

PHILIP N. BRAUN.
